[57] **CLAIM**

The ornamental design for a charger for a wireless telephone, as shown and described.

DESCRIPTION

FIG. 1 is a perspective view of a first embodiment of a portion of a charger for a wireless telephone showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof;

FIG. 7 is a perspective view of a second embodiment of a charger for a wireless telephone showing my new design;

FIG. 8 is a top plan view of the embodiment of FIG. 7;

FIG. 9 is a left side elevational view of the embodiment of FIG. 7;

FIG. 10 is a front elevational view of the embodiment of FIG. 7;

FIG. 11 is a bottom plan view of the embodiment of FIG. 7;

FIG. 12 is a right side elevational view of the embodiment of FIG. 7; and,

FIG. 13 is a rear elevational view of the embodiment of FIG. 7.

The broken line showings throughout the views are for illustrative purposes only and form no part of the claimed design.
